UNITED STATES PATENT OFFICE.

WALTER B. BARROWS, OF EAST LANSING, MICHIGAN.

TONGS.

1,260,302.

Specification of Letters Patent.

Patented Mar. 26, 1918.

Application filed June 11, 1917. Serial No. 174,070.

To all whom it may concern:

Be it known that I, WALTER B. BARROWS, a citizen of the United States, residing at East Lansing, in the county of Ingham and 5 State of Michigan, have invented new and useful Improvements in Tongs, of which the following is a specification.

The object of my invention is to provide efficient and non-corrosive tongs for grasping 10 small objects, especially those treated in hot water, brines, or acid solutions in laboratories, kitchens, and pickle factories.

A further object is to provide tongs of this class having separable legs which may 15 be disjointed at will for the purpose of cleansing the instrument or to substitute a leg of different shape to better conform to the particular object to be grasped.

A further object is to provide tongs composed 20 of resilient fibrous material, such as tough grained wood, in which danger of breaking or splitting at the union of the legs is reduced to a minimum.

In the drawings, Figure 1 is a plan view 25 of one leg of my tongs formed at one end with a tenon; Fig. 2 is a plan view of the companion leg formed at one end with a mortise or socket designed to snugly receive the tenon formed on the first-mentioned leg; 30 Fig. 3 is a perspective view of the tongs; Fig. 4 is a fragmentary side view of a modification of the tenoned leg illustrated in Fig. 1; Fig. 5 is a plan view of the part shown in Fig. 4; Fig. 6 is a plan view of a 35 modification of the socket shown in Fig. 2, designed to receive a triangular tenon, such as is illustrated in Figs. 4 and 5, and Fig. 7 is an end view of the parts illustrated in Figs. 4, 5, and 6, and is taken between the 40 legs of the tongs, the ends of said legs having been cut off as indicated by the section-lining.

Referring to the drawings, I have used the reference numeral 9 to indicate one of 45 the legs of my tongs. This leg 9 consists of a thin, flat piece of wood, formed at one end with a tenon 10 (Figs. 1 and 3). Shoulders 11 at the junction of the tenon and leg limit the depth to which the tenon may enter 50 a mortise in a socket presently to be described. The leg 9 may have a depression 12 cut therein, on the side which, when the two members comprising my tongs are assembled, is the outer side. At the end opposite 55 the tenon 10 and on the inner side of

the leg 9, may be cut teeth or grooves 13, which are placed thereon to more securely grip the objects to be grasped.

The member shown in Fig. 2 comprises a socket 14 and a leg 15, which is similar in 60 material and shape to the leg 9 and has the depression 12 (Fig. 7) and teeth 13 as noted with reference to the leg 9. The outer contour of the socket 14 is that of a truncated wedge and the leg 15 is integral therewith, 65 extending from one side of the base of the wedge. On the opposite side of the wedge and diverging at a slight angle from the leg 15, is a mortise designed to snugly receive the tenon 10. This mortise is preferably a 70 groove 16 having overhanging flanges 17 adapted to snugly fit and retain the tenon 10 in said groove.

The tenon and mortise of the tongs illustrated in Figs. 1, 2, and 3 are rectangular 75 in cross-section, while the alternate form of my device illustrated in Figs. 4, 5, 6, and 7 has a tenon 18, triangular in cross-section and consequently requires a triangular mortise 19 in a socket 20, designed to snugly 80 receive said tenon 18.

In use, the tenon 10 on the removable leg 9 is inserted in the mortise in the socket 14. The user's fingers grasp the legs 9 and 15 at a point slightly below the socket 14 and 85 compress said legs upon the object to be grasped; the depression 12 serving to strengthen the grip of the fingers upon the tongs. When the fingers are removed from the legs, the natural resiliency of the wood 90 causes said legs to spring apart and the object is released.

The operation of the modified form shown in Figs. 4 to 7 is identical with that above 95 described.

It is thus seen that my tongs are manufactured from two small pieces of wood and that their construction is very simple and inexpensive.

The fact that the legs are separable makes 100 the tongs easy to clean and also permits the substitution of a new leg in case of breaking one of them or if a different gripping point is desired.

Having described my invention, what I 105 claim as new and desire to protect by Letters Patent is:

1. In a device of the class described, a resilient leg having an enlargement at one end thereof, said enlargement being formed 110

with a mortise extending longitudinally therethrough, and a second resilient leg formed with a tenon on one end adapted to fit snugly into the mortise in said first-mentioned leg.

5 2. In non-metallic tongs, a beveled socket, a resilient leg formed on one side thereof, and a second resilient leg having a tenon at one end thereof adapted to fit snugly in 10 said socket.

15 3. A pair of separable wooden tongs, one leg of which is formed with a terminal mortise and the other with a terminal tenon adapted to snugly fit said mortise, the inner 15 surfaces of the joint being beveled so that

the legs will, when in normal position, slightly diverge.

4. A pair of tongs of resilient wood, comprising a truncated wedge shaped member having a leg formed on one side of the base 20 thereof, and a beveled mortise cut in the side opposite said leg, said mortise extending at a slight angle to the longitudinal dimension of said leg, and a second leg formed with a tenon on one end thereof designed to snugly 25 fit the mortise in said socket.

In testimony whereof, I have hereunto subscribed my name to this specification.

WALTER B. BARROWS.
